UNITED STATES PATENT OFFICE.

WILLIAM R. STOCKWELL, OF MICHIGAN CITY, INDIANA.

BOILER CONSTRUCTION.

Application filed October 19, 1923. Serial No. 669,455.

This invention relates to improvements in boiler construction.

One object of the invention is to provide, in a boiler of the vertical, cylindrical, sectional type having ash pit and fire doors at the front thereof, auxiliary means for admitting preheated air at the back of the fire box and directing the same to that portion of the combustion chamber which communicates with the flues and, more specifically, is an improvement on the type of boilers shown in my prior Patents 1,128,823 and 1,317,461.

Another object of the invention is to provide a boiler of the type indicated having a passageway extending along the rear wall thereof for establishing communication between the combustion chamber and the flues, wherein an auxiliary air inlet is provided at the rear of the fire box or fire pot having an opening communicating with the chamber adjacent said passageway, of an extent along said rear wall substantially equal to said passageway, said opening being so disposed as to direct air upwardly in a continuous sheet to thoroughly mingle with the products of combustion.

Other objects and advantages of the invention will more clearly appear from the description and claims hereinafter following.

In the drawing forming a part of this specification, Figure 1 is a diametrical, vertical, sectional view, partly broken away, of a boiler, illustrating my improvements in connection therewith. And Figure 2 is a horizontal, sectional view of the back portion of the boiler, corresponding substantially to the line 2—2 of Figure 1.

In said drawing, 10 indicates a cylindrical base or ash pit section of a boiler, 11 a cylindrical water jacketed fire pot section, 12 a water jacketed crown sheet section, 13 a water jacketed dome section, 14 a water jacketed intermediate section, 15 the flue between the dome section and the intermediate section, and 16 the flue between the crown sheet section and the intermediate section. The dome section 13 is provided with a vertical opening 17, adjacent the back of the boiler for establishing communication between the smoke pipe, not shown, and the flue 17, and the section 14 is provided with a vertical opening 17' at the front end thereof for establishing communication between the flues 15 and 16. The crown sheet sec-

tion 12 has an arc shaped opening 18 adjacent the rear wall of the boiler for establishing communication between the flue 16 and the interior of the fire pot. The flues 15 and 16 each have clean out openings at the front and rear of the boiler, the openings at the front being closed by doors 19—19 and the openings at the rear being closed by plates 20—20. Communication between the water jackets of the sections 11, 12, 13 and 14 is established through connecting nipples 21. The ash pit section 10 is provided with a grate 22 and the usual ash pit door at the front thereof, not shown, which also serves as the main air supply inlet to admit the air to the fire pot in a well known manner for updraft grates.

At the front side, the fire pot section 11 has the usual clinker door 23 at the bottom thereof. At the top the section 11 is provided with diametrically opposed openings 24 and 25 disposed respectively at the front and rear sides of the same and both communicating with the interior of the fire pot, the opening 24 being closed by a door 26 and serving as a passage through which the fuel may be fed into the fire pot.

The opening 25 at the back of the boiler in the section 11 is preferably of rectangular outline, in elevation, being defined by a pair of vertical side walls 27—27 lying in planes radial to the vertical axis of the boiler, a bottom wall 28 disposed in a horizontal plane, and the horizontal bottom wall portion 29 of the section 12.

Supported on the wall 28 is an arc shaped block 30 of fire brick or any other suitable refractory material, corresponding in length and height to the opening 25. The block 30 has flat, horizontally disposed, top and bottom faces 31 and 32, a convex outer face 33, a concave inner face 34, and vertically disposed flat side faces 35—35 converging toward the concave inner face 34. The outer and inner faces 33 and 34 of the block are inclined inwardly and upwardly as clearly shown in Figure 1. Along the outer edge, the top face 31 bears against the wall 29 of the section 12 and the side faces 35—35 abut the walls 27—27 of the opening 25. As the side faces of the block and the side walls of the opening converge inwardly, the block will be maintained in position against inwardly displacement by engagement of said faces. The block 30 is cut away at the

outer side along its lower end as indicated at 36, thereby providing a shoulder 37. A suitable shoulder 38, extending upwardly from the wall 28 and which may be applied after 5 the block is inserted, holds the block against outward displacement. The block 30 is thus held in the position shown in Figure 1, projecting inwardly beyond the vertical, inner walls at the rear of the sections 11 and 10 12 and spaced inwardly at the upper end with reference to the outer walls of said sections. The block 30 is provided with an upwardly directed air duct 39 of arc shaped horizontal section extending from the cut 15 away portion 36 of the block to the upper end thereof. The duct 39 is preferably of the same size throughout and the opening at the upper end thereof is of substantially the same arcuate length as the opening 18 20 of the section 12, as clearly shown in Figure 2. When the block 30 is in position, the opening at the upper end of the duct is so disposed that the outer wall of the duct registers with the outer wall of the opening 18 25 in the section 12, as clearly shown in Figure 1. For convenience of description, I have referred to the block 30 as a unitary structure but, as will be understood by those skilled in the art, it may be built into the 30 boiler with bricks or moulded as a single piece.

The opening 25 at the upper end of the section 11 is closed by a plate 40 secured to the outer side of the section 11 in any suitable manner, the same being shown in this instance as secured by bolts 41, the side walls of the opening 25 being suitably cut away to receive the heads of the bolts as clearly shown in Figure 2. The plate 40 is 35 provided with a plurality of vertically disposed air inlet openings or slots 42. A transversely slidable shutter 43, having vertically disposed openings or slots 44, is adapted to coact with the plate 40 to regulate the amount of air admitted through the openings 42 thereof. The shutter 43 is provided with a centrally disposed knob 45 projecting therefrom, engaging the outer side of the plate 40 and having the shank thereof 40 working in a transverse slot 46 in said plate, the knob serving as a means for manipulating the shutter to slide the same to and fro and also acting to hold the shutter to the plate 40.

It will be evident that by properly manipulating the shutter, the same may be moved to various positions to regulate the amount of air admitted through the openings 42 in the plate 40 and that the openings will be completely closed when the shutter is moved to one of its extreme positions and opened widest when moved to the other extreme position. In the drawings, the shutter is shown in the intermediate position. As clearly shown in Figure

2, the plate 39 is spaced from the outer side of the block 30, thereby providing a chamber between the same and the block.

The openings in the plate 40 serve to admit an auxiliary air supply to the combustion chamber, the air passing into the chamber between the plate and the block and entering the air duct through the lower end of the block and passing out through the opening at the upper end of the block in the form of an upwardly directed arcuate thin sheet, immediately adjacent the opening 18 leading to the flues of the boiler. The walls of the block between the air duct 39 and the front and rear of the block form baffles for the incoming air, thereby providing an elongated passageway through which the air must travel before it reaches the combustion chamber.

Inasmuch as the boiler is of the up-draft type, it will be evident that all the products of combustion will necessarily be compelled to pass through the passageway 18, some of the products of combustion entering said passageway substantially vertically and others substantially horizontally, due to the fluting or corrugating of the under side of the crown sheet section 12, as indicated by the shaded lines in Figure 2. This action necessarily induces a swirling of the products of combustion as they pass through the opening 18 and it will be obvious that the greatest heat from direct radiation and impingement of the gases will be present immediately adjacent the opening 18 so that the inner wall of the block 30 becomes intensely heated. As a result of the intense heat concentrated on the inner wall of the block 30, the supplemental air which is admitted through a tortuous passage, is heated to a relatively high degree and is drawn into the passageway 18 at a high velocity and in a continuous arcuate thin sheet. This insures a most thorough inter-mingling of the auxiliary air with the products of combustion at the most desirable point since completion of the combustion takes place both in the upper part of the opening 18 and in the horizontal flue 16.

It will also be noted that the auxiliary feed arrangement can be incorporated in the round sectional type of boiler without any appreciable additional expense, since it is only necessary to slightly modify the fire pot section 11 by leaving the required opening in the rear wall thereof. All other connections and details of the boiler construction remain unchanged so that the cost is not adversely affected.

I have herein shown and described what I now consider the preferred manner of carrying out my invention but the same is merely illustrative and I contemplate all changes and modifications that come within the scope of the claims appended hereto.

I claim:

1. In a boiler, the combination with a fire pot having an opening through which the fuel may be fed into the interior of the pot; of a water jacketed crown sheet above said fire pot, said crown sheet having an opening therethrough adjacent the wall of the boiler for establishing communication between the interior of the fire pot and a flue 10 located above the crown sheet; and flue means at the back of the boiler, said flue means being entirely exterior to the crown sheet and having an inlet communicating directly with the atmosphere and an outlet 15 communicating directly with said opening in the crown sheet at the entrance thereof to supply air directly from the atmosphere to said crown sheet opening.

2. In a boiler of the vertical type, the combination with a fire pot having a door through which the fuel may be fed to the interior; of a horizontally disposed, water jacketed crown sheet section disposed above said fire pot, the said section being provided 25 with a flue opening adjacent the back of the boiler; and an air inlet duct communicating directly with the atmosphere, leading to and terminating at the entrance of said opening, and having an elongated outlet for 30 directing the air upwardly into the entrance of said flue opening in the form of a continuous sheet.

3. In a cylindrical boiler of the vertical type, the combination with a cylindrical combustion chamber having a top wall provided with a flue opening communicating with the back of said chamber; of a heat-conducting baffle element disposed at the rear of said chamber, said baffle element being 40 directly exposed to the heat generated within the chamber, a continuous passageway extending through said baffle element and communicating with the combustion chamber and terminating at the entrance to said flue opening; and an inlet port for said 45 passageway opening through the rear of the boiler and communicating directly with the atmosphere.

4. In a sectional boiler of the character described, the combination with a fire pot section having an up-draft grate, said section having an opening at the rear thereof; of a crown sheet section disposed horizontally and on top of the fire pot section, the crown sheet section having an arcuate 55 passageway at the rear side thereof providing communication from the fire pot to flues above the crown sheet section through which the products of combustion are compelled to pass; and an auxiliary air supply 60 device mounted as a unit in said opening of said fire pot section below said passageway in the crown sheet section, said device having a tortuous air passage therein with an exit orifice substantially co-extensive in 65 length with said passageway and adapted to direct the auxiliary air supply directly into the entrance of said passageway only, said device having an inner wall subject to direct radiation and exposed directly to the 70 current of air in said air passage to thereby insure preheating of the auxiliary air in its passage through said device.

5. In a boiler, the combination with a walled fire pot having an opening through 75 which the fuel may be fed into the interior of the pot and also having an opening through a walled section thereof; of a crown sheet above the fire pot having a flue thereabove, said flue having an opening adjacent 80 the back of the boiler communicating with the interior of the fire pot; and means for admitting air to said fuel opening, including a member seated in the opening of the walled section and closing the same, said member 85 having a passageway therethrough, the entrance to said passageway directly communicating with the atmosphere and the exit of said passageway being coincident with the opening of said flue at the point of communication thereof with the interior of the fire pot.

In witness that I claim the foregoing I have hereunto subscribed my name this 12th day of October 1923.

WILLIAM R. STOCKWELL.
